UNITED STATES PATENT OFFICE.

FRANK PAVLIK, JR., OF WAUKEGAN, ILLINOIS.

DRY CLOSET.

1,289,251.

Specification of Letters Patent. Patented Dec. 31, 1918.

Application filed May 14, 1918. Serial No. 234,500.

To all whom it may concern:

Be it known that I, FRANK PAVLIK, Jr., a citizen of the United States, formerly of Westminster, Colorado, and now residing at Waukegan, in the county of Lake and State of Illinois, have invented certain new and useful Improvements in Dry Closets; and I do hereby declare the following to be a full, clear, and exact description of the invention, such as will enable others skilled in the art to which it appertains to make and use the same.

This invention embodies improvements in dry closets of the indoor sanitary type, and especially relates to that class, which are readily attachable to and detachable from an air outlet conduit for ventilating purposes.

As a rule these closets, in addition to the ventilating features, contemplate the employment of a suitable chemical or the like, preferably in liquid form, introduced into the container for throwing down and deodorizing the arising noxious gases, and while I may also employ such a liquid, where found desirable, nevertheless by my present invention, I aim to accomplish the same ends more satisfactorily by utilizing a source of heat for partially evaporating the contents of the container, to relieve the same of foul odors and other unsanitary conditions, as will hereinafter appear.

The general aims and advantages of these types of closets being fully understood, it will be unnecessary to further initially refer to the specific objects of the present invention, which will be apparent from the following description, though by way of emphasis it may be said that such closets are more peculiarly adapted for use on the farm, homestead, or other outlying localities, where the usual water flushing closets may not be feasibly installed, owing to lack of water facilities and sewerage systems.

With this prefacing statement, and to more clearly understand the present improvements, reference will now be had to the accompanying drawings, illustrating a preferred embodiment of the several details of construction and assembled combination, in which drawings:

Figure 1, is an elevational view of the installed closet, the upper portion thereof being shown partly broken away and in sec-

tion; Fig. 2, is a transverse sectional view through the base standard pipe and heater pan, taken along the line 2-2 of Fig. 1; Fig. 3, is a transverse cross-sectional view on the line 3-3 of Fig. 1; Fig. 4, is a front elevational view of the upper portion of the base standard pipe, being a section on the line 4-4 of Fig. 1; Fig. 5, is a view partly in elevation and partly in longitudinal vertical section through the upper coupling members in their positions before tightening up, the section being indicated by the line 5-5 of Fig. 7; Fig. 6, is a view substantially similar to Fig. 5, but with the coupling members drawn closely together by the rotatable coupling union; Fig. 7, is a vertical cross-sectional view, taken on the line 7-7 of Fig. 6, looking in the direction of the arrow, and with the coupling members but partly drawn together; and Fig. 8, is a vertical cross-sectional view, taken along the line 8-8 of Fig. 6, and looking in the direction of the arrow.

1 designates a base standard pipe, the upper end of which is adapted to be connected with a vent pipe (not shown) leading to the exterior atmosphere, while the lower end thereof is provided with suitably attached vertical side brace members 2, of triangular shape and flanged at their bases, as at 3, for securing the same firmly to the floor, the whole arrangement providing a rigidly braced base vent standard, with the additional advantage of making it feasible to readily install the same very snugly in a corner if desired.

This base standard 1 is formed with a forward opening near its bottom, indicated at 4, to freely receive the projecting end of a lower conduit pipe, hereinafter referred to, and toward its upper end is provided with a communicating laterally projecting short coupling pipe member 5.

The lower opening 4 and the upper opening for the pipe end 5 are each provided with a coöperating damper element 6 and 7, respectively, simply comprising a laterally curved plate, adjustably mounted, to slide against the inside surface of the pipe standard, as by means of a thumb screw 8, riding in associated slots 9 cut through the front wall of the standard.

10 designates an open pan element, preferably supported by short legs 11, which pan

is provided with an opening 12, through one portion of its peripheral wall, and with a tubular extension 13 at a rear position thereof, the projecting end of which extension 5 is in turn adapted to be inserted in the opening 4 of the hollow base standard, and provide a lower communicating conduit pipe between the interior of the pan and said base standard.

- 10 The pan itself is adapted to contain any suitable heating means, whether in the form of an electric heater, a gas stove, or perhaps a simple oil burner might be more desirable in some localities, and even the outlet pipe 15 from a stove fire pot might be conveniently run therethrough, but by way of illustration I have shown the simple expedient of a circular pipe 14, having jet orifices 15, and a connecting branch pipe 16, projecting 20 freely through the peripheral opening 12, adapted to be connected up with a source of gas supply, sufficient space being left to allow for the free entrance of air into the pan through the opening 12. When an electric 25 heater is employed, the lead in and lead out wires may conveniently extend through this opening 12, instead of the gas pipe connection 16.

17 indicates the dry closet container 30 proper, having a suitable bail or handle 18, with the usual removable apertured seat 19, and hinged cover 20 therefor.

The upper rear peripheral wall of this 35 container is provided with a foul air outlet 21, terminating in a projecting tubular extension or upper coupling pipe member 22, which is so spaced vertically, relatively to the lower conduit pipe connection 13, that these upper and lower pipes align in axial 40 registration, respectively, with the coupling member 5 and aperture 4 of the base standard, when the parts are assembled.

The foul air outlet 21 is preferably encompassed by a shield element 23, which is 45 in the nature of a curved plate spaced interiorly of the rear peripheral wall of the container, and forming a pocket terminating substantially above the foul air outlet, with an opening 24 intermediate of the 50 outlet proper and the extreme upper portion of the container. This shield not only increases the working capacity of the container, which may now be filled above the position of the foul air outlet, but also the 55 arrangement is such that a suctional down draft is provided for, as will later appear, functioning to draw down and out, more effectively, any foul air or gases arising and accumulating above the outlet opening, and finally escaping around the seat closure 60 to the interior of the room, which would be manifestly objectionable.

The bottom of the container 17 rests above and closes the open top of the pan 10, being

guided, centered, and supported in place 65 by means of the offset detachably attaching projections 25, as clearly shown.

The projecting end of the base standard coupling pipe member 5 is outwardly flanged, as at 26, and is engaged by the in- 70 turned flange 27 of an enlarged coupling union 28 rotatably mounted on the pipe 5, and adapted to receive the projecting end of the container coupling pipe member 22.

The latter pipe member 22 is provided, on 75 each side thereof, with an outwardly depressed lug 29, being of lengths approxi- 80 mately about one-fourth of its circumference, and these lugs 29 are disposed in the path of a spiral, functioning with a screw- 85 threaded or wedging action in association with complementary internally projecting pins or lugs 30—31 carried by the inner wall face of the coupling member or union 28, as will be clearly understood from the draw- 95 ings.

In assembling or installing the closet, the pan 10 is properly positioned, with the projecting end of the conduit pipe fitted in or in line with the lower opening 4 of the base 90 standard pipe 1. The container 17 is then simply seated thereover, with the upper pipe coupling members 5 and 22 registering in axial alignment but with their adjacent ends slightly spaced apart, as seen in Fig. 5. 95 Upon the rotation of the union 28 to the left, in Fig. 5, it will be observed that the engaging pin 30 thereof will ride up the incline of its spirally associated lug 29, while the opposite pin 31 will reversely 100 ride down its complementary lug 29, causing the ends of the coupling members 5 and 22 to be tightly drawn together, and the whole fixture held securely in that position, as seen in Figs. 1, 6 and 8. Thus it 105 will be apparent that an effective coupling may be speedily made with little or no trouble or effort, while detachment of the container, for emptying and cleaning, may also be facilely accomplished.

When so set up, a suitable liquid deodorizer and germicide may be introduced into the container as usual, if desired, and this regardless of whether or not the heating feature is utilized at all times, for the improved type of upper coupling makes an exceedingly effective joinder between the container and the base standard, so that this improved arrangement alone would provide for conveying off the foul odors by 110 115 way of the vent pipe.

When the heater feature is placed in operation, however, it will not only tend to evaporate and reduce the contents of the container, while driving out therefrom foul 120 odors and destroying the germ life thereof, but also a more intense draft will be created through the vent pipe, by way of the

lower conduit pipe 13 communicating with the hollow base standard, providing a positive suctional force through the upper coupling 5-22, and hence a down draft over 5 the shield 23, thus sucking out all foul odors and gases from the interior of the container. Obviously the lower damper 6 will control the degree of this draft, while the upper damper 7 will likewise control the suctional 10 force through the upper coupling, when the dampers are properly adjusted.

With the foregoing complete disclosure, it is believed that any further description would only be superfluous and prolix, and 15 while it will be understood that I do not make any broad claims to the detachable coupling up of a dry closet container with a vent pipe generally, at the same time, I do not limit myself to the exact details as set 20 forth, excepting as come within the purview of the ensuing claims, when viewed in the light of the specification and contemplating a fair range of equivalents.

What I do claim, as new and practical- 25 able, is:-

1. In dry closet fixtures, the combination with a hollow base standard forming the bottom section of a vent conduit; of a container and suitable apertured seat therefor, 30 said container having a foul air outlet through its upper peripheral wall; tubular coupling means extending from said foul air outlet to the upper portion of said base standard, providing a vent passage there- 35 between; and heating means for said container, functioning to evaporate the contents thereof, substantially as described.

2. In dry closet fixtures, the combination with a hollow base standard forming the 40 bottom section of a vent conduit; of a container and suitable apertured seat therefor, said container having a foul air outlet through its upper peripheral wall; tubular coupling means extending from said foul 45 air outlet to the upper portion of said base standard, providing a vent passage therebetween; heating means for said container functioning to evaporate the contents thereof; and a draft pipe connection leading 50 from said heating means to said hollow base standard for supplying hot air to the latter, substantially as described.

3. In dry closet fixtures, the combination with a hollow base standard forming the 55 bottom section of a vent conduit; of a pan having an open top and inlet means for the entrance of air thereto; a heater element contained within said pan; a container, and suitable apertured seat therefor, supported 60 upon said pan over said heater element, said container having a foul air outlet through its upper peripheral wall; and tubular coupling means extending from said foul air 65 outlet to the upper portion of said base

standard, providing a vent passage therebe- 65 tween, substantially as described.

4. In dry closet fixtures, the combination with a hollow base standard having an aperture toward its lower end and forming the bottom section of a vent conduit; of a pan 70 with a tubular connection between it and said lower aperture; a heater element contained within said pan; a container, and suitable apertured seat therefor, supported upon said pan over said heater element, 75 said container having a foul air outlet through its upper peripheral wall; and tubular coupling means extending from said foul air outlet to the upper portion of said base standard, providing a vent passage 80 therebetween, substantially as described.

5. In dry closet fixtures, the combination with a hollow base standard having an aperture toward its lower end and forming the bottom section of a vent conduit; of a pan 85 with a tubular connection between it and said lower aperture; a heater element contained within said pan; a container, and suitable apertured seat therefor, supported upon said pan over said heater element, said container 90 having a foul air outlet through its upper peripheral wall; tubular coupling means extending from said foul air outlet to the upper portion of said base standard, providing a vent passage therebetween; dampening means for said lower tubular connection; and dampening means for said upper vent passage, substantially as described. 95

6. In dry closet fixtures, the combination with a vent conduit section; of a container 100 and a suitable apertured seat therefor, said container having a foul air outlet through its upper peripheral wall; tubular coupling means extending from said foul air outlet to said vent conduit section, providing a vent passage therebetween; and a pocket shield element, spaced from the interior wall of said container to encompass and open above said foul air outlet, substantially as described. 105

7. In dry closet fixtures, the combination with a vent conduit section; of a container 110 and a suitable apertured seat therefor, said container having a foul air outlet through its upper peripheral wall; tubular coupling means extending from said foul air outlet to said vent conduit section, providing a vent passage therebetween; a pocket shield element spaced from the interior wall of said container to encompass and open above said foul air outlet; heating means for said container functioning to evaporate the contents thereof; and a draft connection leading from said heating means to said vent conduit section for supplying hot air to the latter, substantially as described. 115

8. In dry closet fixtures, the combination with a hollow base standard forming the 120

bottom section of a vent conduit, and provided with inwardly extending triangular side web members functioning as bracing and securing supports as set forth; of a 5 container and a suitable apertured seat therefor, said container having a foul air outlet through its upper peripheral wall; and tubular coupling means extending from

said foul air outlet to the upper portion of said base standard, providing a vent passage therebetween, substantially as described. 10

In testimony whereof, I affix my signature.

FRANK PAVLIK, JR.
